CLAIM

The ornamental design for a file jacket, as shown and described.

DESCRIPTION

FIG. 1 is a top-left perspective view of a file jacket showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a bottom-right perspective view thereof;

FIG. 9 is a top-left perspective view thereof with a binder attachment member folded to a retracted position;

FIG. 10 is a perspective view of another embodiment of a file jacket showing my new design;

FIG. 11 is a front view thereof;

FIG. 12 is a rear view thereof;

FIG. 13 is a top view thereof;
FIG. 14 is a bottom view thereof;
FIG. 15 is a left side view thereof;
FIG. 16 is a right side view thereof;
FIG. 17 is a perspective view of another embodiment of a file jacket showing my new design;
FIG. 18 is a front view thereof;
FIG. 19 is a rear view thereof;
FIG. 20 is a top view thereof;
FIG. 21 is a bottom view thereof;
FIG. 22 is a left side view thereof;
FIG. 23 is a right side view thereof;
FIG. 24 is a perspective view of another embodiment of a file jacket showing my new design;
FIG. 25 is a front view thereof;
FIG. 26 is a rear view thereof;
FIG. 27 is a top view thereof;
FIG. 28 is a bottom view thereof;
FIG. 29 is a left side view thereof;
FIG. 30 is a right side view thereof;
FIG. 31 is a perspective view of another embodiment of a file jacket showing my new design;

FIG. 32 is a front view thereof;
FIG. 33 is a rear view thereof;
FIG. 34 is a top view thereof;
FIG. 35 is a bottom view thereof;
FIG. 36 is a left side view thereof;
FIG. 37 is a right side view thereof;
FIG. 38 is a perspective view of another embodiment of a file jacket showing my new design;
FIG. 39 is a front view thereof;
FIG. 40 is a rear view thereof;
FIG. 41 is a top view thereof;
FIG. 42 is a bottom view thereof;
FIG. 43 is a left side view thereof; and,
FIG. 44 is a right side view thereof;
The portions shown in phantom lines are not part of the claimed invention, but are considered necessary to show environment.
